(57) **CLAIM**

The ornamental design for a hair drying brush, as shown and described.

DESCRIPTION

FIG. 1 is a top, front and right side perspective view of a hair drying brush showing my new design;

FIG. 2 is a front elevation view of the design shown in FIG. 1;

FIG. 3 is a rear elevation view of the design shown in FIG. 1;

FIG. 4 is a left side elevational view of the design shown in FIG. 1;

FIG. 5 is a right side elevation view of the design shown in FIG. 1;

FIG. 6 is a top plan view thereof; of the design shown in FIG. 1; and,

FIG. 7 is a bottom plan view of the design shown in FIG. 1. The broken lines in the drawings depict portions of the hair drying brush that form no part of the claimed design.
